(57) **CLAIM**

The ornamental design for a container for molten metals, as shown and described.

DESCRIPTION

FIG. 1 is a perspective view showing our new design;

FIG. 2 is a right first side elevational view;

FIG. 3 is a left second side elevational view;

FIG. 4 is a front elevational view;

FIG. 5 is a rear elevational view;

FIG. 6 is a top plan view; and,

FIG. 7 is a bottom plan view.

Any broken lines denote probable environmental structure and are not part of the claimed design.
